UNITED STATES PATENT OFFICE

114,193

DESIGN FOR A JEWELRY BOX OR SIMILAR ARTICLE

Florence Miller Mahler, Buffalo, N. Y., assignor to E. B. Mahler Company, Buffalo, N. Y.

Application January 30, 1939, Serial No. 82,664

Term of patent 3½ years

To all whom it may concern:

Be it known that I, Florence Miller Mahler, a citizen of the United States, residing at Buffalo, in the county of Erie and State of New York, have invented and produced a new, original, and ornamental Design for a Jewelry Box or Similar Article, of which the following is a specification, reference being had to the accompany drawing forming part thereof; and in which

Figure 1 is a perspective view of a jewelry box or similar article showing my new design; and

I claim:

The ornamental design for a jewelry box or similar article, as shown.

FLORENCE MILLER MAHLER.
